CLAIM

The ornamental design for a point-of-sale device casing as shown and described.

DESCRIPTION

FIG. 1 is a front, right-side, and top perspective view of a point-of-sale device casing showing the design.

FIG. 2 is a rear, left-side, and bottom perspective view of the point-of-sale device casing of FIG. 1.

FIG. 3 is a front view of the point-of-sale device casing of FIG. 1.

FIG. 4 is a rear view of the point-of-sale device casing of FIG. 1.

FIG. 5 is a right side view of the point-of-sale device casing of FIG. 1.

FIG. 6 is a left side view of the point-of-sale device casing of FIG. 1.

FIG. 7 is a top view of the point-of-sale device casing of FIG. 1; and,

FIG. 8 is a bottom view of the point-of-sale device casing of FIG. 1.

The features shown in broken lines form no part of the claimed design.

1 Claim, 8 Drawing Sheets
